CLAIM

The ornamental design for an infant's crib, substantially as shown.

DESCRIPTION

FIG. 1 is a perspective view of an infant's crib showing my new design;

FIG. 2 is a front elevational view thereof showing the gate in its lowered position;

FIG. 3 is an end elevational view thereof;

FIG. 4 is a rear elevational view thereof with the gate in its raised position;

FIG. 5 is a top view thereof; and

FIG. 6 is a bottom view thereof.
